UNITED STATES PATENT OFFICE.

MAX MAURAN, OF NIAGARA FALLS, NEW YORK, ASSIGNEE TO THE MATRIESSON
ALKALI WORKS, INC., OF NEW YORK, N. Y., A CORPORATION OF VIRGINIA.

MULTIPLE-UNIT TANK CAR.

Application filed February 7, 1922. Serial No. 584,642.

To all whom it may concern:

Be it known that I, MAX MAURAN, a citizen of the United States, residing at Niagara Falls, in the county of Niagara, State of New York, have invented certain new and useful Improvements in Multiple-Unit Tank Cars; and I do hereby declare the following to be a full, clear, and exact description of the invention, such as will enable others skilled in the art to which it appertains to make and use the same.

This invention relates to improvements in multi-tank cars designed for the transportation of a plurality of tanks containing liquefied gases.

In the transportation of liquefied gases, such as liquefied chlorine, liquefied sulphur dioxide, etc., it has been necessary heretofore to ship the liquefied gases in relatively small containers, especially designed and constructed for withstanding the high pressures of the liquefied gases contained therein. The shipment of the liquefied gases in this way involves an excessive cost for the containers and for their shipment (both when full and returning when empty). The amount of the liquefied gases that can be transported in such a container is moreover small, and, for large shipments, an excessive number of the small individual containers is necessary. If tank cars having a single large tank are used for transporting such liquefied gases, it is difficult to prevent injury or weakening of the tanks by corrosion, particularly with corrosive gases and where the tanks are insulated to protect them from overheating during transportation; while the transportation of a single tank car of the liquefied gases presents a potential risk of a major order in case of accident to the car.

According to the present invention, a multi-tank car is provided which enables liquefied gases to be transported in large containers and in carload lots, with equal or greater safety than when shipped in small containers, and with added advantages in the handling and shipment of large quantities of the liquefied gases.

The present invention provides a multi-tank car for transporting a relatively large number of tanks, for example, each of about one ton capacity, the tanks being constructed to withstand safely the pressures to which the liquefied gases are subjected, and

the tanks being individually mounted and supported on the car and securely held in place during transportation, but being so secured and held that they can be readily removed and replaced when desired.

In transporting tanks of a liquefied gas, which is confined under a heavy pressure, and which may be highly poisonous and destructive if released from the container, it is important to insure that the tanks shall be securely held in place without danger of accidental removal from the car and also securely held from motion on the car, either transversely or longitudinally. If the tanks are placed on end, with their axes vertical, the pitching and rolling motion of the car is exaggerated on the tank.

The multi-tank car of the present invention is constructed to hold a relatively large number of tanks securely and without danger of accidental displacement or movement on or from the car, even with the varied motions of pitching and rolling, and of sudden stopping or starting, to which the car may be subjected in transit, and which subject the load of the car to the same varied motion.

According to the present invention, the car structure itself is so constructed as to provide individual cradles for holding a considerable number of tanks on the car, and, in connection with the series of individual cradles, there is provided means for holding the tanks on the cradles and preventing them either from transverse motion, transversely of the car, or motion longitudinally of the car, as well as preventing their removal from their respective cradles until released therefrom. The nature and advantages of the invention will more fully appear from the following more detailed description.

In the preferred construction of the invention, the cradles are longitudinally arranged, rather than transversely, so that the drums or tanks will be transversely arranged on the car and will be prevented by the cradles and holding means from rolling motion longitudinally of the car, while also being held from movement transversely of the car on the cradle supports.

The tanks which are used in the multi-tank car of the invention may vary somewhat in their size and construction. They may be, for example, of about one ton capacity, and preferably of uniform or sub-

stantially uniform cross section and may have heads even with the ends of the tanks or bulged outwardly, or heads which are sunken and arranged to provide a well-defined rim or chime on each end. The tanks or drums may be made of metal with the ends welded in and may be provided with blocks at the ends together with suitable closures permitting filling and discharging of the contents. The tanks will, of course, be constructed to withstand the excessive pressure to which they are subjected by the liquefied gases which they are designed to contain. Nevertheless, although constructed to withstand heavy pressures, their weight in proportion to the weight of the liquefied gases which they contain is radically less than in the case of the ordinary small metal containers commonly used for the transportation of liquefied gases. The tanks may have an overall length, for example, of about eighty inches, or somewhat less than the width of an ordinary freight car.

In transporting liquefied gases under pressure, it is important to provide for the release of the gases in case of fire or undue heating of the tanks before the pressure (due to the heat) becomes excessive. In order to provide for this release of the contents of the drums or tanks, they are provided with safety devices such as fusible plugs which will melt at a relatively low temperature, for example, around 150° F. In case of injury or overheating of one of the tanks or drums, its contents will be released in a gradual and progressive manner while the other tanks may retain their contents without injury.

The car construction is equally adapted for the transportation of full containers (filled with the liquefied gas) and empty containers, so that the car can be shipped with a load of full containers and returned with a load of empty containers, without delay other than that occasioned by the unloading or loading of the car. The car is moreover so constructed as to permit ready loading and unloading, while it is nevertheless designed and constructed to provide, as a part of the car structure, supporting and bracing means as well as cradles for holding the tanks with their axes horizontal and transverse of the car. In connection with each cradle and tank, means is provided for detachably securing the tank to the cradle so that the tank will be securely held in place, but so that it may nevertheless be unfastened and removed when desired, and a new tank, either empty or filled, inserted to take its place.

In constructing the car, the cradles and supporting means therefor are carried directly by the car frame so that the provision of the usual platform of a freight car is made unnecessary. However, the ar-

rangement of a series of tanks transversely of the car presents an impediment to the easy and safe passage of the brakeman along the car, especially when the car is in rapid motion. In order to overcome this difficulty, the car is provided with special passageways along the sides of the car, and also at the ends, so that the brakeman may easily and safely pass along by the ends of the tanks from one car to another without danger, even during rapid travel of the car in transit. The car construction as a whole, accordingly, enables a series of tanks of large capacity to be safely transported and held in place, but detached and removed and replaced when desired, while also enabling the brakeman to travel along the car, on gangways at the ends of the drums, with the construction and arrangement of the car as a whole nicely balanced and with a load distributed in a substantially uniform manner transversely of the car.

The accompanying drawings illustrate the preferred construction of the multi-tank car of the invention, the construction being shown in a somewhat conventional and diagrammatic manner, but it is intended and will be understood that the invention is illustrated by and not limited to the specific construction so illustrated and described.

In the drawings,

Fig. 1 is a plan view of the approved car, part of the car being shown with the upper portion removed;

Fig. 2 is a side elevation with their parts in section;

Fig. 3 is a section on the line 3—3 of Fig. 1;

Fig. 4 is a section on the line 4—4 of Fig. 1, certain parts being removed;

Fig. 5 is an end view of one of the tanks held in place on the car;

Fig. 6 is an enlarged side view of the clamping device shown in Figs. 4 and 6, parts being in section;

Fig. 7 is a plan view of a modified construction showing an alternative form of clamping mechanism, parts of the car being omitted;

Fig. 8 is a partial side view of the same construction;

Fig. 9 is a sectional detail of the locking mechanism of Figs. 7 and 8;

Fig. 10 is a view taken at right angles to that of Fig. 9;

Fig. 11 is an end view of one of the containers and a part of the car body showing an alternative form of the invention; and

Fig. 12 is a partial side view of the same.

In the embodiment of the invention shown in Figs. 1 to 6 the frame or body of the car is made up of a central sill 1, constructed as a box girder, having arranged transversely, though at suitable intervals, cross girders 2, while at the ends of the car other gird-

ers and frame members 3 are provided of greater strength than the girders 2, the trucks (not shown) supporting the car at the girders 3. A girder 4 is arranged at each end of the sill 1 and the ends of the girders 3 and 4 are connected by channel plates 5, while suitable braces are arranged between the ends of the girder 4 and the sill 1, the construction being such that a suitable framework is provided at the ends of the cars for supporting and holding the car as a whole upon the trucks.

As shown more particularly in Fig. 4, the transverse girders 2 are strongly constructed and extend for only a short distance on each side of the central sill while lighter frame members 2^a extend outwardly to the side of the car and are braced by other members 2^b, also of lighter construction. The girders 3 and 4 are somewhat similar but extend out to the side of the car.

The short cross beams or girders 2 carry, near their outer ends, longitudinal channel plates 7 extending the full length of the car. Upon these channel plates 7 are a series of cradle members 8 suitably spaced apart and adapted to support the tanks or containers 9 in the manner illustrated. To further strengthen the structure and hold the cradles against transverse movement, braces 10 are arranged in the manner shown, and are connected respectively to the central sill 1 and to the cradles 8 on each side of the car. It will thus be seen that the effective car structure supporting the cradles extends only a short distance from the central sill, that is, the distance indicated in Fig. 4 between the cradles 8, while the cradles themselves are spaced apart and so constructed and arranged, with concave seating surfaces, to form seats for the cylindrical containers, in which the containers are held transversely to the length of the car in properly spaced relation.

While the cradles themselves tend to hold the containers from rolling movement longitudinally of the car, and while the weight of the containers themselves tends to hold them from transverse movement on the cradles, nevertheless, in order to prevent displacement by the sudden or abrupt movements to which the car may be subjected additional means is provided for clamping the containers on the cradles and for holding them both against transverse movement or from rolling movement longitudinally of the car. The clamping means for holding the containers to the cradles may take any preferred form. Certain forms of clamping means suitable for the purpose are illustrated in the drawings, although, from the broader aspects of the invention, the specific construction of the clamping means can be varied, and clamping devices of the varying construction can be used, provided the tanks

or drums are clamped securely in place on the cradles.

The clamping means illustrated in Figs. 4, 5 and 6 comprises rods 11 pivotally supported at one end by brackets 12 secured to the frame of the car. Two of these rods are provided for each container, one at each end. At their outer ends the rods are threaded and have mounted thereon hook members 13 carried by nut members 14. As shown in Fig. 6, each nut is annularly recessed at 15 and each hook has a flange 16 entering the recess to rotatably connect the nut to the hook so that the hook will be raised and lowered as the nut is screwed and unscrewed. Removal of the nut is prevented by a head 17 on the rod. This form of clamping means is especially adapted for use with containers having a well defined rim or chime at their ends over which the hook 13 can be secured. To engage the hooks with the containers, the nut is turned outwardly until the hook will pass over the end of the rim or chime, then the nut is turned inwardly until the hook is brought into close engagement with the chime, thus securely clamping the container at both ends to the framework of the car.

When the container is thus secured in place, it is clamped to the framework of the car so that it cannot move transversely and also so that it cannot be raised, while the cradles themselves, in conjunction with the clamping means, absorb the longitudinal thrust or force of the containers lengthwise of the car when the car is started or stopped and when the containers would normally tend to roll lengthwise of the car unless they were securely held in place and prevented from such movement.

In Figs. 7 to 10 there is shown another suitable form of clamping mechanism comprising straps or bands 18 curved to fit the containers 9^a, the ends of which are turned upwardly, as indicated at 24 and engage recesses 23 on the under side of washer members 22, which, in turn, are held down by nuts 21 threaded on rods 19 or 19^a secured to the cradles. The rods 19 extend upwardly between the containers while the rod 19^a at the end of the car extends upwardly beyond the last container and has the strap pivotally secured thereto. It will be evident that by tightening the nuts 21 the pressure of the bands on the containers may be increased to the desired extent, thus clamping the drum securely to the cradles; while by removing the nuts 21 and washers 22 the straps 18 can be removed, thus permitting the removal of the drums. In order still further to prevent or reduce the tendency toward transverse movement of the drums on the cradles, the drums themselves may, for example, have circumferential projections or bands 26 spaced apart so that

they will fit within the cradles and so that the transverse movement of the drums will be prevented by the engagement of the projections or bands with the cradles. These 5 ribs or bands will also engage the straps 18 which will further tend to prevent accidental transverse movement of the drums on the car.

In Figs. 11 and 12 another alternative 10 construction is shown. The clamping mechanism at each end of each container comprises a pair of flexible members or chains 27, each connected at one end to a cradle member by means of eye bolts 28, 15 and the two adjacent members or chains being arranged to engage each other by means of adjustable hook members 29 engaging a link of the cooperating chain.

When the chains are secured together in the 20 manner illustrated in Figs. 11 and 12, the drums will be securely clamped down on their respective cradles. In order further to neutralize any tendency of the drums to move transversely on the car, abutments 31 25 may be provided, arranged to extend up at each end of the containers so that, if the containers tend to move transversely on their cradles, they will engage the abutments 31 and be prevented from further 30 transverse movement. This arrangement, as well as the constructions above described, enable the drums to be securely clamped in place on their respective cradles and held both from rolling or longitudinal movement 35 on the car as well as from transverse movement thereon.

It will be evident that a series of large 40 tanks containing, for example, about one ton of the liquefied gas, are so irregular in their shape, when arranged on the car, that it is difficult for the brakeman to pass along the tops of the containers, particularly when the car is in rapid motion. In order to provide for the safe passage of the brakeman, 45 the drums are made of a length less than the width of the car, and an outer structure or a gangway is provided at the ends of the drums or tanks so that the brakeman may safely pass along either side of the car, and 50 so that the containers themselves will always be accessible for inspection at either end. This outer passageway or gangway is supported by the members 2^a, and, near the ends of the car, by the cross members 3 and 4. 55 Running boards 32 are carried by these members, each member having an inner upwardly extending guard member 33 secured in place by bolts 34, each of which has an L-shaped plate 35 at its upper edge, through 60 which the bolt passes. A hand rail 36 is supported at each side of the car, outside the gangway, by means of upright posts 37 carried by the transverse girders. A somewhat similar guard rail 38 is arranged at each end

of the car, the ends of these guard rails being 65 spaced from the guard rails 36 as shown more particularly in Fig. 1. A similar platform member or gangway member is arranged at the ends of the car so that the brakeman can readily pass from one car to 70 another and along the length of the multi-tank car without difficulty, and with protection while so passing.

It will accordingly be seen that the multi-tank car of the present invention is of relatively simple construction, with a framework extending the length of the car and by which the tanks are supported, and to which they are secured, so that the tanks or containers themselves may be considered a 80 component and integral part of the car when the car is loaded either with full or empty containers, the car and containers being so constructed, and the containers being so held on the car, that the containers become 85 in fact an integral part of the car and partake of all of its movements during transit. When the containers are removed, only the skeleton framework is left.

The construction of the multi-tank cars 90 is nevertheless such that the car may readily be unloaded and loaded by releasing the clamping devices and raising the separate containers from their respective seats. In loading the car, the tanks are placed in the 95 cradles and properly centered and are then clamped in place by one or another of the clamping devices illustrated, or by other suitable clamping means, so that they are securely held in place in the manner above described. Since the cradles are a part of the car framework and structure, and since the containers are securely held to the cradles, there can be no movement of the containers 100 with respect to the car or with respect to 105 each other.

When the car has reached its destination, the clamping devices may be loosened and the individual containers may be removed, for example, by means of an overhead crane 110 or trolley, and carried to their place of storage or show house. Empty tanks can then be placed on the car and fastened in place in the manner above described. This makes unnecessary the holding of the car 115 until the individual tanks have been emptied and enables a car to be unloaded and then loaded with empty tanks and returned to the place of refilling where the empty tanks 120 can be detached and removed and the car 125 again reloaded with full tanks. The car, moreover, is of integral construction in the sense that the supporting and securing members thereof form a part of the car structure and only the tanks are intended to be 130 detached and removed.

With a car having a capacity of about thirty thousand pounds, for instance, about

fifteen cradles would be provided, each adapted to hold a tank weighing about one ton. The load thus carried is in the form of separate units, each individually supported and held, and each separated from engagement or possibility of impact with those adjacent to it.

It will thus be seen that the invention provides a valuable and improved construction of tank cars for safely transporting liquefied gases in large containers and with safety, even though the containers are themselves subjected to a high internal pressure, and even though the liquid in the containers may be subjected to more or less violent agitation from the motion of the car during transit. The liquefied gases can thus be transported with a minimum of danger, even though the liquefied gases may be of a corrosive character; while the individual containers themselves are capable of ready inspection and testing. This inspection and testing is of particular importance where the gases transported are corrosive in character, such as chlorine or sulphur dioxide. One advantage of the construction shown and described, is that it facilitates testing of the containers, in that they can be removed from the car to a testing floor.

30 The multi-tank car of the present invention is adapted for the transportation of non-corrosive products, such as casing-head gasolene, where it is important to prevent escape of highly volatile dissolved gases, 35 and where the containers are required to withstand the pressure which such gases may exert. The safety plugs, one or more of which is provided for each container, are indicated at 40 in the drawing and may be 40 of any suitable construction, for example, of a low melting point alloy melting at about 150° F., so that when the containers are exposed to excess heat, the plugs will fuse, permitting the contents of the containers to 45 flow out in relatively small streams which will give warning of the escape of the gas and prevent explosion of the container due to excessive pressure resulting from overheating.

50 While I have illustrated and described the preferred embodiments of the invention, yet I do not limit myself to the specific construction of the embodiments illustrated, inasmuch as variations and modifications can
55 be made therein without departing from the spirit and scope of the invention, as set forth in the accompanying claims.

I claim:

1. A car of the class described, comprising a frame having a plurality of seats extending transversely thereof, a cylindrical container in each seat, and means for clamping the containers to the seats.

2. A car of the class described, comprising

ing a body composed of a central longitudinally extending sill and transverse girders, and supporting concave seats extending transversely of the car body, substantially cylindrical drums in the seats, and means for clamping the drums in the seats against movement in any direction. 65
70

3. A car of the class described, comprising a body composed of a central longitudinal sill and transverse girders, plates secured to the girders on each side of the sill and extending longitudinally of the body, each plate carrying spacing blocks, the blocks of the plates registering and forming between said blocks seats, substantially cylindrical containers in the seats, and means engaging the containers for holding them in the seats. 75 80

4. A car of the class described, comprising a body composed of a central longitudinal sill and transverse girders, a cradle supported by the girders, and provided with seats extending transversely of the car body, drums in the seats, means for clamping the drums against movement in any direction, running boards supported at the ends of the girders, and a hand rail outside of each running board.

5. A car of the class described, comprising a body composed of a central sill and transverse girders, plates secured to the girders at each side of the center of the car and carrying spacing blocks, said blocks forming between them seats, cylindrical containers in the seats, and means for holding the containers in place on the seats, the girders being extended beyond the ends of the containers, and carrying running boards, and hand rails outside the running boards.

6. A car of the class described, comprising a body composed of a central sill and transverse girders, plates secured to the girders at each side of the center of the car and carrying concave seats, cylindrical containers in the seats, and means for holding the containers in place on the seats, the girders at the ends of the cars having their ends connected and being braced against each other. 103 110

7. A car of the class described, comprising a frame having a plurality of seats extending transversely thereof, and a cylindrical container in each seat, and means for holding the containers to the seats, said holding means comprising hooks for engaging the ends of the containers, rods pivoted to the frame on which the hooks are slidably mounted, and a nut threaded onto each rod and having a rotatable connection with the adjacent hook, whereby to constrain the hook to travel with the nut.

hook to travel with the nut.

8. A car of the class described, comprising an open frame, seats supported by the frame in spaced relation transversely of the

car, and cylindrical containers clamped to the seats with their axes transverse to the length of the car.

9. A car of the class described, comprising an open frame, seats supported by the frame in spaced relation and cylindrical containers clamped to the seats.

10. A car of the class described, comprising a frame having a plurality of seats extending transversely thereof, adapted to hold cylindrical containers and means for clamping the containers to the seats.

11. A car of the class described, comprising a body composed of a central longitudinally extending sill and transverse girders and supporting concave seats extending transversely of the car body, said seats being adapted to hold cylindrical drums and means for clamping drums in the seats against movement in any direction.

12. A car of the class described, comprising a body composed of a central longitudinal sill and transverse girders, plates secured to the girders on each side of the sill and extending longitudinally of the body, each plate carrying spacing blocks, the blocks of the plates registering and forming between said blocks seats, said

seats being adapted to hold cylindrical containers, and clamping means to engage containers and hold them in the seats.

13. A car of the class described, comprising a body composed of a central longitudinal sill and transverse girders, a cradle supported by the girders and provided with seats extending transversely of the car body, said seats being adapted to hold drums, means for clamping drums against movement in any direction, running boards supported at the ends of the girders and a hand rail outside of each running board.

14. A car of the class described, comprising a frame having a plurality of seats extending transversely thereof, said seats being adapted to hold cylindrical containers and means for holding containers to the seats, said holding means comprising hooks for engaging the end of the containers, rods pivoted to the frame on which the hooks are separately mounted and a nut threaded on to each rod and having a rotatable connection with the adjacent hook whereby to constrain the hook to travel with the nut.

In testimony whereof I affix my signature.

MAX MAURAN.
